UNITED STATES PATENT OFFICE.

MAX J. VEST, OF DENVER, COLORADO.

INTERNAL-COMBUSTION ENGINE.

Application filed July 20, 1921. Serial No. 486,126.

This invention relates to internal combustion engines and its primary object is to provide an engine construction in which simplicity, strength and practicability are effectively combined. With this object in view, I form the exhaust and intake manifolds inside the cylinder walls of a body section of the engine, and arrange the intake and exhaust valves in a head section which is removably supported upon the body section.

It is another object of my invention to arrange the valves in the cylinder head, so as to be readily accessible for repair or adjustment when the latter is removed from the engine body, and a further object is to provide in connection with the cylinder head, a water and dust-proof casing, which encloses the valves and their operating mechanism, and which also encloses the spark plugs of the engine to protect them from dirt and moisture. Still another object of the invention is to provide a novel system of conduits to pre-heat and super-heat the constituents of the combustible mixture separately and collectively before it enters the cylinders of the engine, and a further object is to provide a cylinder of an internal combustion engine with a divided explosion chamber, the compartments of which are separately equipped with spark plugs and intake and exhaust valves. The above and other objects, all of which will fully appear in the course of the following description, are attained by the construction and arrangement of parts shown in the accompanying drawings, in the various views of which like parts are similarly designated, and in which

Figure 1 is a vertical fragmentary section taken through a cylinder of the engine along a line 1—1 of Figure 3;

Figure 2, a diagrammatic representation of the arrangement of conduits in the cylinder walls;

Figure 3, a composite view showing horizontal sections taken on the lines 3—3, 4—4, and 6—6, Figure 1;

Figure 4, a view similar to Figure 1 showing a modification in the construction of the engine; and

Figure 5, a fragmentary section along the line 5—5, Figure 4.

In the drawings, the reference numeral 2 designates the body part of a multi-cylinder engine, and 3 the head of the same, including a spark plug cage 40 and valve cages 41,

which are slidably supported on the body part and detachably connected thereto by bolts or other suitable means. The body has equidistantly arranged cylinder bores or piston chambers 4 which open in the upper surface thereof, and its walls are made sufficiently heavy to embody the intake and exhaust manifolds and other conduits of the engine.

In the construction shown in Figure 1, the manifolds and conduits are formed integrally with the body by channels in the walls thereof, and in the modification illustrated in Figure 4 the several conduits are cast en bloc and inserted in open ended recesses in the cylinder walls. The arrangement of the conduits is the same in each case, and a description of that of the construction illustrated in Figure 1 will suffice to explain the other. The engine as shown in the drawings is of the duplex type, i. e., it has two sets of valves for each of its cylinders, two intake and exhaust manifolds, and two carburetors. By this arrangement of parts, it is possible to operate the engine at a greatly reduced expenditure of motive fluid when its full efficiency is not required, and it avoids complete incapacitation of the engine should the valves, ignition system or carburetor at either side thereof become ineffective by the breakage or derangement of their parts.

Since the system of valves and conduits of one side of the engine is identical to that of the other side of the same and operates independently thereof, I will explain the arrangement of one system only and apply the same characters of reference to corresponding parts of the other system. The intake manifold 5 which connects the discharge port of the carburetor with the cylinders through the intermediary of the respective intake valves, is formed in the cylinder wall adjacent the piston chambers and it connects with the valve chambers by means of upwardly extending branches 6, which open in the upper surface of the engine body. The exhaust manifold 7, formed parallel to the intake manifold, has a corresponding number of upwardly extending branches 8 which open in the top of the engine body to register with the chambers of the exhaust valves of the several cylinders, and at the points where these branches extend across the intake manifold, the latter is offset below the same. A straight conduit 9 of smaller diam-

eter, closed at its ends and axially coincident with the aligned upper portions of the intake manifold, connects with the exhaust manifold by branches at the point at which it passes through the spaces above the depressed portions of the intake manifold, so that a part of the spent gases of combustion which enter the exhaust manifold from the cylinders of the engine must pass through the conduit, to superheat the explosive mixture in the intake manifold before it enters the explosion chambers of the cylinders. A conduit 10, of smaller diameter, passing through the exhaust manifold, is at one end open to the atmosphere and connects at its other end with a pipe 16 leading to the air intake port of the carburetor which in the drawings has been designated by the reference character 12.

It is obvious that in the operation of the engine its walls are heated to a considerable extent and this heat is utilized not only to superheat the mixture passing through the intake manifold, but also to preheat the liquid fuel before it enters the carburetor. With the last mentioned object in view, a passage 13 is formed in the cylinder wall in close proximity to the exhaust manifold and conduits 14 and 15 are attached at opposite ends of this passage for its connection with a fuel intake port of the carburetor and the fuel reservoir of the motor vehicle. The discharge port of the carburetor is connected to the intake manifold, preferably adjacent each cylinder of the engine, by a channel 17 formed in the cylinder wall, which connects with the intake manifold as at 18, and with a conduit 19 leading to the carburetor, through an opening in the outer surface of the wall. It will be evident that by the provision of this auxiliary path for the combustible mixture through the heated cylinder wall, it is still further preheated, and that by the heat applied exteriorly to the channel as well as to the intake manifold and interiorly of the latter by the exhaust gases passing through the conduit 9, the mixture is delivered to the engine in a thoroughly dry and vaporized condition and at a consequently high degree of efficiency.

This very desirable object in the operation of an internal combustion engine is furthermore promoted by preheating the air and gaseous fuel before they enter the carburetor and as it is attained by utilization of the heat naturally generated in the operation of the engine, it entails no additional expense.

The spark plug cage 40 which rests upon the flat upper surface of the body and upon the valve cages, has in connection with the open cylinder ends, explosion chambers which are divided into two compartments 20 by jacketed ridges 21 of V-shaped section.

When the piston 22a in the cylinder

reaches the end of its explosion stroke, as shown in Figures 1 and 4 of the drawings, it practically engages with the apex of the ridge and thereby closes the two compartments of the explosion chamber. Each compartment has in its outer side an admission port 22 and an exhaust port 23, and each compartment is equipped with a separate spark plug 24 which passes through an opening in the corresponding side of the V-shaped ridge.

Above the ridge is formed a space 25 for the conductors of electricity 26, connected with the several spark plugs of the engine, and in order to prevent tangling of these conductors and confusion in their arrangement, they are preferably laid in troughs formed in the space by upwardly extending partitions 27.

The valve cages, disposed at opposite sides of the spark plug cage, have valve chambers 28 and 29, which connect separately with the openings in the upper surface of the engine body at the ends of the branches of the intake and exhaust manifolds. The valves 30 and 31 are slidably supported in bushed bearings 32 and normally engage with seats in the openings 22 and 23 which connect their respective chambers with the explosion chambers of the engine. Springs 33 coiled around the valve stems bear upon transverse pins 34 to yieldingly maintain the valves in engagement with their seats, and rocker arms 35 in cooperation with cams 36 on shafts 37 serve to periodically unseat the valves in the operation of the engine, said shafts and rocker arms being mounted upon a block which forms an integral part of the respective valve cages.

The entire cylinder head, including the valve cages and spark plug cage, is enclosed by a water and dust proof casing 38, removably fastened by bolts 39, and the members of the head are detachably fastened to the body section of the engine by bolts not shown in the drawings. The casing, as shown in Figure 1, may be composed of three sections which are separately removable to afford access to one or the other of the valve cages or to the spark plug cage, as may be required.

It will be apparent that the composite parts of the head are readily detached from the body of the engine, and when separated from the same, afford easy access to the valves and their seats for repairs, re-grinding, or adjustment, and that the casing protects the spark plugs and the valve operating mechanism from dust, dirt, and moisture, while the parts are readily accessible for renewal or repair.

Having thus described my improved engine construction, I desire it understood that modifications in the arrangements of its component parts and the method of their

connection may be resorted to within the spirit of my invention, as defined in the hereunto appended claims.

What I desire to secure by Letters Patent 5 is:

1. An internal combustion engine, comprising an engine body having piston chambers, spark plugs connected at the explosion ends thereof, channels formed exteriorly of 10 the chambers to receive conductors of electricity leading to the spark plugs, and a removable casing covering the spark plugs and the channels.
2. In an internal combustion engine, a one piece engine body hollowed to provide a piston chamber, one wall of said chamber formed with a channel for the passage of fuel, said wall being adapted to conduct heat generated by the combustion of fuel in the 20 piston chamber to fuel passing through said channel, said channel being connected at one end to a source of fuel supply, and at the other end to a carburetor.
3. An internal combustion engine comprising in combination with a carburetor and a source of fuel-supply, a one-piece engine body hollowed to form a piston chamber and having in the wall of said chamber an intake channel, a preheating channel connected with the intake channel and with the fuel outlet of the carburetor, an exhaust channel, a hollow core in the intake channel connected with the exhaust channel, a channel in the exhaust channel connecting the air-intake of the carburetor with the atmosphere, and a channel connecting the fuel intake of the carburetor with the source of fuel.
4. An internal combustion engine comprising in combination with a carburetor and a source of fuel supply, a one-piece engine body hollowed to form a piston chamber and having in the wall of said chamber an intake channel connected with the fuel-outlet of the carburetor, an exhaust channel, a hollow core in the intake channel connected with the exhaust channel, a channel in the exhaust channel connecting the air-intake of the carburetor with the atmosphere, and a channel connecting the fuel intake of the carburetor with the source of fuel.
5. An internal combustion engine comprising in combination with a carburetor and a source of fuel-supply, a one-piece engine body hollowed to form a piston chamber and having in the wall of said chamber an intake channel, a preheating channel connected with the intake channel and with the fuel-outlet of the carburetor, and a channel connecting the fuel intake of the carburetor with the source of fuel.
6. An internal combustion engine comprising in combination with a carburetor

and a source of fuel supply, a one-piece engine body hollowed to form a piston chamber and having in the wall of said chamber an intake channel connected with the fuel-outlet of the carburetor, a channel connecting the air-intake of the carburetor with the atmosphere, and a channel connecting the fuel-intake of the carburetor with the source of fuel.

7. An internal combustion engine comprising a one-piece engine body having a piston chamber and in the wall thereof, a channel for the passage of fuel, said chamber and the channel being open in an end of said body, a valve cage separably supported by said body, a spark plug cage separably supported by said valve cage and having an explosion space connecting with the opening of the piston chamber, said valve cage having ports connecting respectively with the opening of the channel and with the explosion space of the spark plug cage, and a valve in the valve cage controlling the flow of fuel between said ports.

8. An internal combustion engine comprising a one-piece engine body having a piston chamber and in the wall thereof, a channel for the passage of fuel, the chamber and the channel being open in an end of said body, a valve cage, a spark plug cage separably supported by said valve cage and having an explosion space connecting with the opening of the piston chamber, said valve cage being separably supported by the body and having ports connecting respectively with the opening of the channel and with the explosion space of the spark plug cage, a valve in the valve cage controlling the flow of fuel between said ports, and mechanism for the operation of the valve, supported by the valve cage.

9. An internal combustion engine comprising a one-piece engine body having a piston chamber and in the wall thereof a channel for the passage of fuel, the chamber and the channel being open in an end of said body, a valve cage, a spark plug cage separably supported by the valve cage and having an explosion space connecting with the opening of the piston chamber, said valve cage being separably supported by the body and having ports connecting respectively with the opening of the channel and with the explosion space of the spark plug cage, a valve in the valve cage controlling the flow of fuel between said ports, mechanism for the operation of the valve, supported by the valve cage, and a removable casing enclosing the cages.

In testimony whereof I have affixed my signature.

MAX J. VEST.
